US00D441715S

(12) **United States Design Patent**
Sasaki et al.

(10) Patent No.: **US D441,715 S**
(45) Date of Patent: ** May 8, 2001

(54) **ROTOR OF ELECTRIC MOTOR**

(75) Inventors: **Kenji Sasaki**, Fukui; **Teruo Tamura**, Nara, both of (JP)

(73) Assignees: **Matsushita Electric Industrial Co., Ltd.**; **Matsushita Refrigeration Co.**, both of (JP)

(**) Term: **14 Years**

(21) Appl. No.: **29/117,649**

(22) Filed: **Jan. 28, 2000**

(30) **Foreign Application Priority Data**

Jul. 29, 1999 (JP) 11-20681

(51) LOC (7) Cl. **13-01**

(52) U.S. Cl. **D13/122**

(58) Field of Search D13/118, 122; 310/156, 201, 216, 254-260, 261-271

(57) **CLAIM**

The ornamental design for a rotor of electric motor, as shown and described.

DESCRIPTION

FIG. 1 is a perspective view of the top, front and right side of a rotor of electric motor showing our new design;

FIG. 2 is a front elevational view thereof;

FIG. 3 is a top plan view thereof;

FIG. 4 is a rear elevational view thereof;

FIG. 5 is a bottom view thereof;

FIG. 6 is a left side elevational view thereof; and,

FIG. 7 is a right side elevation view thereof.
